RHODE ISLAND, ASSIGNEES TO THE NITROGEN CORPORATION, OF PROVIDENCE,
RHODE ISLAND, A CORPORATION OF RHODE ISLAND.

HIGH-PRESSURE CIRCULATING PUMP.

Application filed June 29, 1921. Serial No. 481,206.

To all whom it may concern:

Be it known that we, EDWIN H. ARNOLD and WILLIAM T. WAKEFORD, citizens of the United States, residing at Coventry and Warwick Downs, respectively, in the county of Kent and State of Rhode Island, have invented certain new and useful Improvements in High-Pressure Circulating Pumps, of which the following is a specification.

10 This invention relates to a high pressure circulating pump especially adapted for use in connection with the handling of gases under high pressure, such, for example, as hydrogen and nitrogen.

15 In the use of highly diffusive gases under high pressures such as are employed, for example, in the synthesis of ammonia, it is exceedingly difficult to place the gases under the pressures at which the synthetic operation may be most efficiently carried out by means of the pumps heretofore used, by reason of the fact that such pumps are not adapted to withstand the high pressures to which they are subjected and the slightest 25 leak which may develop tends to lower their efficiency to such a point as to render them practically useless. Moreover, the high pressures employed occasion such a strain upon the parts as to make frequent repairs necessary, which, when the parts to be repaired are inaccessible, causes costly delays.

30 One object of the invention is to provide an improved pump of this character wherein means is provided for maintaining the piston under a substantial degree of back pressure whereby the amount of force utilized in raising the gases to the required pressure is considerably less than would otherwise be required and the danger of leakage past the piston rings is correspondingly reduced.

35 Another object of the invention is to provide a construction wherein the number of the parts is greatly reduced to prevent leakage of the gases from the pump cylinder, and the arrangement of the operating parts simplified to permit ready access thereto for the purpose of repair, while at the same time providing a construction capable of 40 withstanding high pressures.

45 A further object of the invention is to provide a construction wherein the pump casing may be maintained under high pressure while means is provided for prevent-

ing undue axial movement of the crank shaft 55 by reason of the pressures in the casing.

Other objects and advantages of the invention relate to details of construction and improved methods of operation as will be more fully set forth in the detailed description to follow.

Referring to the drawings:

Fig. 1 is a longitudinal vertical sectional view of the pump taken along line 1—1 of Fig. 3.

Fig. 2 is a transverse vertical section taken along line 2—2 of Fig. 1.

Fig. 3 is a top plan view of the pump cylinders, and,

Fig. 4 is a detail sectional view of the head 70 portion of one of the pump cylinders showing the valve construction.

In the embodiment of the invention illustrated herewith 1 designates the shaft casing provided at opposite ends with aligned openings 2 of sufficient size to permit the insertion of the crank shaft 3. The casing 1 may be formed as an integral casting, the openings 2 in the opposite ends thereof being of sufficient size to permit the insertion of the offset crank portions of the shaft 3 therewithin, or it may be formed from separate sections rigidly bolted together. A pair of end plates 4 and 5 of similar construction are secured to opposite ends of the crank 85 shaft casing 1 by means of bolts 6 threaded into the casing and provided with nuts 7 for clamping the end plates firmly against the ends of the casing to prevent leakage therearound. The casing 1 is provided with an 90 annular shoulder 8 adjacent to each of the openings 2 formed therein, and a correspondingly formed shoulder 9 on the cooperating end plate fits thereagainst, suitable packing 10 being interposed between 95 the cooperating shoulders to insure a tight fit therebetween and prevent the escape of gases from the casing.

Since the end plates 4 and 5 are of similar construction only one of these parts will be 100 described in detail, it being understood that the descriptive matter relating thereto applies equally well to the other of said end plates and its adjunctive devices.

The end plate 4 is provided with a portion 11 projecting outwardly therefrom which serves to provide an extended bearing for the adjacent end of the crank shaft 3. A

shouldered bore extends through the projecting portion 11 of the end plate as well as the main part thereof within which is rotatably mounted the adjacent end of the shaft 3. 5 Within the more constricted portion of the bore a bearing 12 formed of Babbitt metal or other suitable material is provided for the shaft, said bearing being preferably provided with an enlarged portion 13 projecting 10 within the casing for a purpose which will be more fully described hereinafter. Suitable packing material 14 is positioned about the shaft in the enlarged portion of the bore and is held in place by a suitable 15 gland 15, which is in turn held in position and may be suitably adjusted by a cap nut 16 threaded upon the exterior surface of the outwardly projecting portion 11 as indicated at 17. 20 The shaft 3 is provided with crank portions 20, properly located relative to the cylinders, to which the connecting rods 22 are attached by means of split-bearings or other suitable devices 24. 25 The crank shaft is provided with a shouldered portion 27 adjacent each end of the casing upon which is positioned a bearing ring 28. An opposed bearing ring 29 is mounted upon the enlarged portion 13 30 of each bearing 12 previously described, and a series of balls 30 are interposed between the bearing rings 28 and 29 to provide thrust bearings for the crank shaft and prevent excessive movement of the shaft 35 in an axial direction under the high pressure maintained within the crank casing. Positioned between each of the bearing rings 29 and the inner surface of the respective end plate is a ring 32 for taking up wear 40 upon the thrust bearing and assisting in the proper positioning of the shaft longitudinally of the casing. The rings 32 may if desired, be split to automatically take up the wear to a certain extent and prevent 45 undue play in the bearings or if the rings 32 are integral they may be readily removed when desired and replaced by others by merely removing the end plates from the ends of the shaft. 50 In devices of this character when high pressures are maintained in the crank casing it has been found that leakage may develop around the shaft in one of the bearings and that when such leakage once 55 occurs the high pressure in the crank case causes the leak to increase rapidly and tends to force the shaft bodily in an axial direction. The provision of thrust bearings at the ends of the shaft serves to retain the 60 shaft in proper position at all times and thus prevent the danger of a slight leakage being increased by axial movement of the shaft as well as to insure retention of the shaft in the proper position for actuating 65 the plungers.

Mounted upon the shaft casing 1 are a pair of integral cylinders 36 each of which is provided with a base portion 37 adapted to fit within an opening 38 formed in the upper portion of the casing and provided 70 with an annular shoulder 39 for engagement with a similar shoulder 40 carried by the casing. Suitable packing 41 may be interposed between the meeting faces of the shoulders 39 and 40 to prevent leakage from 75 the casing between the meeting surfaces. Each of the cylinders 36 is provided with an annular flange 42 having openings 43 for the reception of bolts 44 whereby the cylinders may be firmly clamped to the casing. 80 Nuts 45 are threaded upon the bolts 44 and serve to draw the shoulders 39 and 40 into close engagement to prevent leakage therebetween.

The particular construction of the cylinders constitutes an important feature of the invention, as cylinders constructed in separate parts bolted together and of such materials as cast iron and cast steel have been found to be incapable of withstanding the pressures to which the gases are subjected therein without leakage through the joints or even through the pores of the material itself. In order to overcome these difficulties we have formed the cylinders 36 of forged steel and made them integral throughout, thus dispensing with all joints and utilizing a material capable of withstanding the pressures employed. Forged steel has been found to be sufficiently impermeable to gases such as nitrogen and hydrogen as to prevent escape of the gases through the material to such an extent as to interfere with the operation of the pump. 90 Each cylinder 36 is provided with a main bore 48 within which is reciprocably mounted a piston 50, provided with a plurality of piston rings 51 and suitably connected to one of the connecting rods 22 for reciprocation by the crank shaft. Each cylinder is also provided with a pair of bores 53 and 54 formed in the head portion thereof for the reception of inlet and exhaust valves respectively. The bore for the inlet valve may be somewhat larger in diameter than that for the outlet valve as the pressure under which the gas enters the cylinder is less than that at which it is discharged. The bore 53 is preferably formed to provide an annular shoulder 55 to be engaged by a correspondingly formed shoulder on the valve block 56, as shown in Fig. 4 of the drawings. The valve block 56 is provided with an axial bore for the reception of the stem 57 of the inlet valve 58, and the valve stem 57 is provided with a head 59 engaged by a coiled compression spring 60 for normally holding the valve 58 in engagement with the valve seat. An annular groove 62 is formed in the outer surface of the valve 110 120 130

- block from which extend a plurality of passages 63, opening into the cylinder through the valve seat, and which are closed by the valve 58 when the valve is seated.
- 5 The annular groove 62 communicates with an inlet pipe 64 through which the gases are conveyed to the cylinder from a source of supply which in the present instance may be a compressor wherein the gases have been 70 initially compressed prior to their entry into the cylinder. The upper portion of the bore 53 is internally threaded, as shown in Fig. 4 of the drawings, and a plug 67 is threaded into the upper portion of the bore 10 a sufficient distance to bear against the upper surface of the valve block 56 and hold the same securely seated in the head portion of the cylinder. The plug 67 is provided with a recess 68 in the inner end 20 thereof for the reception of the valve stem 57.

Mounted in the bore 54 is a valve block or sleeve 70 which serves as a seat for the outlet valve 71 slidably mounted therein, and which 25 rests upon a shoulder 72 formed in the head portion of the cylinder. An opening 73 in the sleeve 70 communicates with the outlet pipe 74 as well as with an annular groove 75 formed in the interior of said sleeve whereby 30 the outlet pipe 74 may be placed in communication with the interior of the cylinder when the inlet valve 71 is raised. The upper portion of the bore 54 is internally threaded, as shown in Fig. 4 of the drawings, and a 35 plug 78 is threaded therein and bears against the valve block or sleeve 70 to hold the same firmly seated against the shoulder 72 formed in the head portion of the cylinder. A stem 79 projects downwardly from the plug 78 40 and is surrounded by a coiled spring 80 which bears against the valve 71 to normally hold the same in contact with its seat on the sleeve 70.

From the above description it will be seen 45 that the pump cylinders being of integral construction, that is, the main body portion and head portion of each cylinder being formed integral, there are no joints or connections through which leakage of the gases 50 may take place, while, by reason of the novel arrangement of the parts they may be as readily and easily constructed as though they were formed in sections. It will be seen that the bore 48 can readily be formed in the cylinder block and then the bores for the inlet and 55 outlet valves formed as well as the openings for the inlet and outlet pipes, all of these openings being readily formed from the outside of the cylinders with the same facility 60 as though the cylinders were sectional. Moreover, the construction of the valves is such as to permit their being readily removed at any time for purposes of replacement or repair by merely removing the corresponding 65 plugs which hold the same in place. The

operative mechanism of each valve is securely held against accidental displacement by means of the plugs threaded into the head portion of the cylinder and bearing against the valve parts to hold them firmly in contact with their respective seats.

The upper portion of each cylinder is cored out as indicated at 81 to form spaced annular flanges 82 and 83 to which a cylindrical shell 84 may be secured to provide a 75 water jacket for cooling the cylinder, water being circulated therethrough in any desired manner as by means of pipes 85 and 86.

The crank casing is preferably maintained under a pressure substantially equal to that 80 at which the incoming gases are admitted to the cylinders by means of a pipe 88 connecting the inlet pipe 64 with the interior of the crank casing 1. The source of supply or reservoir from which the gases are drawn 85 together with the cubical contents of the cylinder being relatively large as compared with the piston displacement, the return movement of the piston will have no appreciable effect in compressing the gases in the 90 crank casing, and in the case of two cylinders being employed, as in the embodiment shown herewith, the tendency of one piston to compress the gases in the crank casing on its return stroke will be counterbalanced by 95 the advance of the other piston. It is proposed to utilize the structure shown herewith, for example, in acting upon gases already under a pressure of from 800 to 1000 pounds per square inch, and to compress such 100 gases in the pump so that they may be delivered therefrom under pressures of from 1200 to 1500 pounds per square inch. It will be obvious therefore that the advantages to be obtained by admitting such gases, to 105 the crank casing whereby a substantially constant back pressure will be maintained on the pistons serves to greatly reduce the amount of power necessary to be employed in the further compressing of the gases. By 110 means of the present arrangement there is practically no circulation of the gases through the crank casing with consequent liability of contamination by contact with oil or other materials therein. While for the purpose of illustration certain specified 115 pressures have been stated as capable of being utilized in the operation of the mechanism for the purpose of compressing gases in the manner described, it is to be understood 120 that the mechanism is not limited to use under the pressures the same or substantially the same as set forth, but that the pressures mentioned are cited merely as illustrative of one use of the structure.

Having described our invention, what we claim is:

1. A high pressure circulating pump comprising a crank casing provided with openings at opposite ends thereof, end plates 130

secured to said casing and serving as closures for said openings, said end plates being provided with bearings for supporting a crank shaft, a crank shaft positioned in said 5 casing and rotatably supported by said bearings, integral cylinders secured to said casing and each provided with a main bore communicating with the interior of the casing and bored inlet and outlet valve passages having their axes substantially parallel with the axis of the main bore, and pistons reciprocably mounted in the main bores of said cylinders and operatively connected with said crank shaft.

10 2. A high pressure circulating pump comprising a crank casing, a crank shaft mounted within said crank casing, bearings for

rotatably supporting said crank shaft, an integral cylinder secured to said casing and provided with a main bore communicating with the interior of said casing and bored inlet and outlet valve passages communicating with said main bore, inlet and outlet valve structures mounted in said valve passages, a piston, reciprocably mounted in the main bore of said cylinder and operatively connected with said crank shaft, and means for preventing axial movement of said crank shaft in said casing.

20 In testimony whereof we have affixed our 25 signatures.

EDWIN H. ARNOLD.
WILLIAM T. WAKEFORD.
